UNITED STATES PATENT OFFICE.

ERNEST B. FORD, OF UNIONVILLE, NEW JERSEY.

TUBE CLEANER.

Application filed March 27, 1926. Serial No. 97,820.

This invention relates to a tube cleaner, and while it is adaptable for use in the cleaning of tubes of various types and kinds, it is nevertheless particularly adapted for the 5 cleaning of condenser tubes and the like.

An object of the present invention is to provide a tube cleaner which is of simple and inexpensive construction, but which will be easy to use and efficient in its operation.

10 A further object is to provide a tube cleaner comprising parts whereby it is adjustable so as to serve with equal efficiency in the cleaning of tubes of different sizes.

15 A further object is to provide a tube cleaner comprising one part constructed and arranged for loosening the sediment from the walls of the tube and another part constructed and arranged to scavenge out the loosened material.

20 A further object is to provide a tube cleaner which is adapted to be driven through the tube by water pressure, and in which a suitable part of the water employed for driving the cleaner through the tube is utilized for 25 assisting the cleaner in cleaning the tube.

25 A more detailed object is to provide a tube cleaner comprising a brush and a piston to provide efficient means for connecting said two elements together, and to provide 30 means whereby the piston may be expanded to cause it to properly fit within tubes of varying sizes.

35 Other objects and aims of the invention, more or less specific than those referred to above, will be in part obvious and in part 40 pointed out in the course of the following description of the elements, combinations, arrangements of parts and applications of principles constituting the invention; and 45 the scope of protection contemplated will be indicated in the appended claims.

50 In the accompanying drawings which are to be taken as a part of this specification, and in which I have shown merely a preferred 45 form of embodiment of the invention:—

55 Fig. 1 is a combined side elevational and sectional view of a tube cleaner constructed in accordance with this invention, the cleaner being shown in association within a dotted line representation of a tube to be cleaned.

Fig. 2 is a view similar to a portion of Fig. 1 but showing the piston in elevation.

Fig. 3 is an end view of the piston seen in Figs. 1 and 2, and

55 Fig. 4 is a view similar to Fig. 2 but show-

ing in section a modified construction of the piston.

Referring to the drawings for describing in detail the structure therein shown the reference character L indicates the brush of the 60 tube cleaner while the reference character G indicates the piston of the cleaner. These two elements are connected together by a central rod H.

The brush may be of any desired construction. The rod H preferably extends centrally therethrough, and in fact preferably constitutes the core or carrier for the brush bristles 1 which project radially therefrom in all directions so that a cylindrical brush is provided which is well adapted for rubbing along the interior surface of the tube as 2 to be cleaned. The brush is preferably of slightly greater diameter than the interior of the tube so that the bristles 1 will necessarily be somewhat bent over and made thereby to generate a considerable pressure, and a consequent scrubbing action, radially against the walls of the tube.

The brush L may be of any desired length, 80 either more or less than as illustrated.

The forward end of rod H preferably projects beyond the forward end of the bristle portion of the brush, as at 3, and serves to support a suitably rounded protector head 85 as 4 which may be formed of any suitable material but which is preferably of molded soft rubber or the like.

The rear end portion of the rod H is formed into a suitably reduced threaded extension 5 which projects through a central bore 6 of the piston G.

90 The piston G may be formed of any suitable material but the material now thought to be best adapted for its purposes is soft rubber, preferably molded into the shape as indicated.

95 The reduction in diameter of the rod H, for producing the threaded extension 5 provides a conical portion 7 which engages with in the forward end of bore 6 and tends to prevent or restrict the telescoping movement of the piston G forwardly over the rod. The threads of the extension 5, being in engagement with the rubber walls of the bore 6 also tend to prevent this telescoping movement and, together with the conical portion 7, practically prevents any telescoping movement beyond a given desired point, and here it may be noted that the forward end of the 100

bore 6 may either be enlarged to greater width than the central portion, so as to receive the conical portion of rod H, or the elasticity of the material of the piston may be utilized to permit the necessary expansion of the bore, as may be found expedient.

The rear end of bore 6 is enlarged to provide a cone shaped seat 8 in the rear end of the piston, and into this seat engages a screw threaded wedge 9 the purpose of which is to spread the material of the piston more or less as the wedge is screwed to a greater or less extent into the seat.

The walls of the seat 8 may be molded with threads to receive the threads of the wedge if desired but owing to the pliable and elastic character of the material from which the piston is formed such molded threads are not at present thought to be necessary since the threads of the wedge, being preferably of brass, will readily sink into the walls of the seat and form a sufficiently efficient thread grip upon said walls to properly feed the wedge backwardly or forwardly whenever the wedge is rotated in one direction or the other.

As an additional means for holding the wedge in any position to which it is rotated, as well as for assisting in the retention of the rod H, the wedge 9 is preferably formed with a central socket as 10 therein arranged to receive the extension 5 of the rod and said socket being screw threaded to interengage with the threads of the extension.

Thus whenever the wedge is rotated so that its external threads, in engagement with the walls of the seat 8, feed the wedge in one direction or the other, its internal threads will follow the threads of the extension 5 in like manner. Any slight difference as between the pitches of the external and internal threads of the wedge will be readily compensated for by a negligible amount of slippage between either or both the rod H, and or, the wedge, and the material of the piston.

Whenever it is desired to enlarge the diameter of the rear portion of the piston it is simply necessary to rotate the wedge 9 inwardly to thereby radially expand the resilient and elastic material of which the piston is formed. This action will be readily understood by reference to the dotted lines 11 in Fig. 1 which illustrate how the rear portion of the piston would be enlarged to properly fit against the walls of the tube being cleaned.

In order to facilitate the easy expansion of the piston by means of the wedge 9 it may be desirable to provide a plurality of radial slits as 12 in the end of the piston so that portions of the piston at opposite sides of the slits may be spread away from each other to a suitable degree under the spreading influence of the wedge.

It is also a feature of this invention to so shape the exterior surface of the piston as to

provide one or more scavenging edges as 13—13 thereon adapted to engage and clean off from the tube any and all objectionable material which has been loosened by the brush L.

It is also a feature of this invention to provide the piston with suitable means, as for instance the grooves 14—14 whereby a proper quantity of the water, or other fluid, which is used as a propelling element for driving the cleaner through the tube, will be allowed to pass the piston for co-operating as a flushing medium to assist the brush L in loosening the objectionable material from the tube walls.

The grooves 14—14 are formed upon the exterior surface of the piston extending between the opposite ends of said piston, and they are preferably suitably spiralled so as to insure the scavenging action of the piston without leaving any part of the circumference of the tube unscavenged.

The structure shown in the modification Fig. 4 illustrates the use of a metallic sleeve as 15 within the piston G. This sleeve may be held within the material of the piston either by frictional grip or by being vulcanized therein, as may be found expedient. Its interior is screw threaded as at 16 and into the forward end engages a threaded extension as 17 of the brush carrying rod H. The wedge for spreading the rear end of the piston is here indicated by the reference character 18 and it is formed with a threaded extension 19 which threads into the rear end of the sleeve, the wedge portion being in this case smooth and unthreaded and the interengagement of the threads 19 within the sleeve being depended upon to move the wedge forwardly or backwardly upon rotation of the wedge.

In this modification also the piston is shown without either the slits 12, the scavenging edges 13 or the slots 14, although it will be understood that if desired these features may be as well employed here as in the structure seen in Figs. 1 to 3.

As will be readily understood by those skilled in the art to which this invention belongs, the purpose of providing for convenient manual adjustment of the diameter of the piston is to enable said piston element to be readily brought to a proper piston fit within the tube to be cleaned. In order to properly perform its work of cleaning the tube the piston must be suitably tight against the surface of the tube to insure an efficient scavenging action. It should also preferably be so tight as to require considerable fluid pressure behind it to drive it through the tube, since in this way the fluid which passes through the grooves 14—14 will be forced through said grooves under considerable pressure and be thus better able to flush through the brush L in assisting the brush in the performance of its duties. And yet the piston

must not be so tight as that an available amount of fluid pressure, whatever it may be, would be unable to drive the cleaner through the tube.

5 Slight adjustment of the diameter of the piston will thus determine the efficiency, or lack of efficiency, of the cleaner.

It may be here noted also that although the drawings Figs. 1 to 3 suggest the use of 10 radial slits to facilitate the adjustment of the diameter of the piston, these slits are not intended to provide passages for fluid past the piston. As a matter of fact the outer 15 ends of the slits will be efficiently closed during the operation of the device, this due to the pressure of the piston against the walls of the tube, and the consequent spreading action of the material of the piston.

As many changes could be made in this 20 construction without departing from the scope of the invention as defined in the following claims, it is intended that all matter contained in the above description or shown in the accompanying drawings, shall be interpreted as illustrative only and not in a 25 limiting sense.

Having thus described my invention, what I claim as new and desire to secure by Letters Patent is:—

30 1. A tube cleaner comprising a brush and a rubber piston connected together, and means manually adjustable to utilize the yielding and elastic quality of the rubber to alter the diameter of the piston.

35 2. A tube cleaner comprising in part a piston formed of rubber, and means manually adjustable to utilize the yielding and elastic quality of said rubber for altering the diameter of the piston.

40 3. A tube cleaner comprising in part a piston formed of elastic material, and a wedge carried by said piston manually adjustable to alter the diameter of the piston at will.

45 4. A tube cleaner comprising in part a piston formed of elastic material, and a screw threaded wedge carried by said piston manually rotatable with respect to the piston to thereby utilize the screw threads in effecting an alteration in the diameter of the piston.

50 5. A tube cleaner comprising a brush and a piston, means connecting said brush and piston together, the piston being of alterable diameter, and a part engaging said connecting means and said piston manually adjustable relatively thereto to thereby alter the diameter of the piston.

55 6. A tube cleaner comprising a brush and a piston, a member carried by the brush extending into a central bore of the piston, the piston being of alterable diameter, and a part engaging said member and said piston serving to hold said member connected with the

piston and being manually operable to alter the diameter of the piston at will.

7. A tube cleaner comprising in part a piston formed of rubber, said piston having radial slits therein, and a wedge member manually operable to utilize said slits in altering the diameter of the piston at will. 65

8. A tube cleaner comprising a brush and a piston arranged in co-axial alignment and adapted to be driven through a tube by fluid pressure applied against the piston, the piston being formed of rubber and having a groove extending longitudinally along its 75 surface to constitute a passage-way through which a portion of the fluid may pass the piston for reaching the brush to assist the brush in cleaning the tube. 70

9. A tube cleaner comprising in part a piston, said piston being of rubber and being formed with a plurality of annular rubber scavenging edges thereon, and means whereby the diameter of the piston is manually adjustable at will to cause said scavenging edges 85 to engage more or less tightly against the walls of the tube being cleaned. 80

10. A tube cleaner comprising a brush and a piston, the piston being formed of soft rubber and having a central bore therethrough, 90 the brush having a rod connected therewith extending into the bore of the piston, and a wedge arranged upon said rod within the piston rotatably adjustable thereon to alter the diameter of the piston and to serve in 95 holding the piston connected with the rod.

11. A tube cleaner comprising a cylindrical piece of soft rubber having a central bore therethrough, a plurality of annular scavenging edges formed exteriorly upon said piece 100 of rubber, means by which to expand said piece of rubber to alter the external diameter thereof, and the external surface of said piece of rubber having a groove extending longitudinally thereof for the purpose described. 105

12. In a tube cleaner, the combination with a brush, of a rubber piston separably connected therewith, and means manually adjustable to utilize the yielding and elastic quality of the rubber to alter the diameter of the piston. 110

13. A tube cleaner comprising a brush and a piston arranged in co-axial alignment and adapted to be driven through a tube by fluid pressure applied against the piston, and the piston having a longitudinally extending groove formed spirally along its outer surface through which a portion of the fluid may pass the piston for reaching the brush 120 to assist the brush in cleaning the tube. 115

In testimony whereof I affix my signature.

ERNEST B. FORD.
